UNITED STATES PATENT OFFICE.

RANDALL M. DIXON, OF STOCKTON, CALIFORNIA.

COMPOUND SCREW JACK.

Application filed March 20, 1924. Serial No. 700,516.

To all whom it may concern:

Be it known that I, RANDALL M. DIXON, a citizen of the United States, residing in Stockton, county of San Joaquin, State of California, have invented certain new and useful Improvements in Compound Screw Jacks; and I do declare the following to be a full, clear, and exact description of the same, reference being had to the accompanying drawings, and to the characters of reference marked thereon, which form a part of this application.

This invention relates to improvements in lifting jacks, my main object being to provide a jack of the above named general character so constructed that a very powerful raising effect will be had, and loads may be lifted through a considerable distance, while at the same time the jack when its parts are fully contracted, will occupy but relatively little vertical space.

While my jack may of course be used for any purpose for which such an implement is suitable, I have particularly designed it for automobile service.

Automobiles must frequently be jacked up, usually to raise an axle so that a tire may be removed and replaced following a puncture or blowout.

In such cases, and especially when the wheels are equipped with the oversize or balloon tires now coming into vogue, the axle will be lowered a considerable distance when such a tire loses its air and becomes flat. Under such conditions, very frequently the ordinary small jacks if short enough when contracted to fit between the ground and axle, have not the lifting range necessary to raise the axle the required distance, or if they have such lifting range, they are too tall even when fully telescoped or contracted, to fit under the axle when the tire is flat.

The result is that the operator must resort to various time-taking and laborious expedients in order to be able to jack up his car.

My improved jack eliminates the above troubles, by having as before stated, a great range of lift coupled with an extremely compact or short size when contracted.

A further object of the invention is to produce a simple and inexpensive device and yet one which will be exceedingly effective for the purpose for which it is designed.

These objects I accomplish by means of

such structure and relative arrangement of parts as will fully appear by a perusal of the following specification and claims.

In the drawings similar characters of reference indicate corresponding parts in the several views:

Fig. 1 is a vertical section of the jack with the lifting members partly raised.

Fig. 2 is an exterior elevation of the jack in its fully contracted form.

Fig. 3 is a cross section on the line 3—3 of Fig. 1.

Referring now more particularly to the characters of reference marked thereon, the numeral 1 denotes a vertical cylindrical casing or pedestal, mounted in the lower end of which is a base pad 2. Turnably mounted on said pad is a bevel gear 3 meshing with a pinion 4 whose shaft or spindle 5 is journaled in a bearing boss 6 formed with the casing 1. The shaft 5 slopes up at a certain angle, and is bored with a square hole as at 7 or in any manner to non-turnably receive a pin on the lower end of a ratchet turning handle or lever of any suitable form. The outer end of the member 5 is preferably provided with a knurled collar 8, whereby the pinion may be turned by hand if desired.

The gear 3 has a hollow shaft 9 mounted therewith and projecting upwardly into the casing for a certain distance and concentric therewith.

This shaft has longitudinal splines 10 on its outer periphery which engage and slide in splineways 11 cut in the bore of a tubular sleeve 12. This sleeve is exteriorly threaded throughout its length with left hand and preferably square threads 13 of a certain pitch, which engage with cooperating threads 14 cut in the bore of the casing for a certain distance downwardly from the upper end thereof.

In the upper end of the bore of the sleeve 12 are cut right hand threads 15, also preferably square, which cooperate with similar threads 16 cut for the full length of a stem 17, the bore of the gear-shaft 9 being of a size to freely receive said stem therein.

On the upper end of the stem is a fixed pad 18 of suitable size and design. Another pad 19 is adapted to rest on the pad 18, being hinged as at 20 to a transverse member 21 projecting radially under and beyond the pad 18. In this manner, the upper pad 19 may be swung down out of the way if its use is not desired, thus enabling the dis-

tance from the ground to the load carrying pad to be altered much quicker than by raising or lowering the stem itself, when initially setting the jack up to be used.

5 The member 21 projects beyond the pad 18 on the side thereof opposite the hinge 20 and has secured thereto a vertical stem 22 depending downwardly therefrom and 10 slideable in a sleeve 23 guided by a horizontal boss 24 projecting from the upper end of the casing 1. The members 22 and 23 have outwardly and inwardly projecting shoulder portions 25 at their lower and 15 upper ends respectively, so that when the stem 22 has been raised a certain distance, its shoulder will engage the shoulder on the sleeve 23 and the latter will then, and not until then, be raised also. The purpose of this telescoping structure is to prevent 20 rotation of the jack stem 17.

In operation, if the pinion 4 is turned to the right, the gear 3 and member 12 will be turned in a clockwise direction. The member 12 being threaded into the casing 25 with left hand threads, such rotation will cause the member 12 to be advanced from the casing. At the same time, the stem 17 being screwed into the sleeve 12 with threads oppositely cut to those on the outside of the 30 sleeve, and being held against rotation, is likewise advanced from the sleeve 12 with the advancement of the latter from the casing. The different screw threads should be of such relative pitch that the lower end of 35 the sleeve 12 reaches the lower end of the cooperating threads in the casing at the same time as the lower end of the stem 17 reaches the lower end of the cooperating threading in the sleeve.

40 The distance that these members may travel in the respective members in which they are mounted being substantially equal, both the stem and sleeve should therefore advance the same distance for each revolution of the sleeve.

It will therefore be seen that by reason of the telescoping feature of the raising members, the height to which the pad may be raised from the top of the casing is considerably greater than the total height of 50 the casing itself.

While the threads on the sleeve are specified as left hand and those on the stem 17 as right hand, this is only because the pinion 4 is presumed to be turned to the right to raise the stem. If the pinion was intended to be turned in the opposite direction, or the gear was arranged so as to turn counter-clockwise with the turning of the pinion to

the right, then the relative arrangement of 60 the threads on the sleeve and stem would be reversed.

From the foregoing description it will be readily seen that I have produced such a device as substantially fulfills the objects of 65 the invention, as set forth herein.

While this specification sets forth in detail the present and preferred construction of the device, still in practice such deviations from such detail may be resorted to as do 70 not form a departure from the spirit of the invention, as defined by the appended claims.

Having thus described my invention what I claim as new and useful and desire to secure by Letters Patent is:

75 1. A jack comprising a casing, a lifting stem normally telescoped therein and capable of being projected therefrom, a rod fixed to and extending parallel with the stem to move vertically therewith, a sleeve slidably mounted on the casing and arranged to remain stationary during the initial movement of the rod, and means whereby when the rod has moved a predetermined distance the sleeve will then be raised with any further movement of such rod. 80

2. A jack comprising a casing, a lifting stem normally telescoped therein and capable of being projected therefrom, a rod fixed to and extending parallel with the stem 90 to move vertically therewith, a sleeve slidably mounted on the casing and arranged to remain stationary during the initial movement of the rod, the rod and sleeve having co-engaging shoulders on their upper 95 and lower ends respectively whereby to cause them to move as a unit after the rod has moved a predetermined distance.

3. The combination in a jack of the type described, having a casing and a jack stem 100 movable vertically therethrough, of a guide means, such means including a sleeve mounted for vertical sliding movement relative to the casing, the bore of the sleeve adjacent its upper end being reduced to form a shoulder, 105 a rod of a diameter equal to that of the reduced bore of the sleeve and slideable therethrough, an enlarged head on the rod within the sleeve whereby after the rod moves a predetermined distance through the sleeve 110 the head will engage said shoulder and thereafter the rod and sleeve will move together as a unit, the rod being connected at its upper end to the upper end of the jack stem. 115

In testimony whereof I affix my signature.

RANDALL M. DIXON.
